UNITED STATES PATENT OFFICE.

ELOF R. LEONARD, OF WOODCLIFF, NEW JERSEY.

SASH-GUIDE.

1,115,844.

Specification of Letters Patent.

Patented Nov. 3, 1914.

Application filed June 29, 1914. Serial No. 847,900.

To all whom it may concern:

Be it known that I, ELOF R. LEONARD, a citizen of the United States, and resident of Woodcliff, Bergen county, State of New Jersey, have invented certain new and useful Improvements in Sash-Guides, of which the following is a specification.

My invention relates to devices for holding pivoted sashes at desired angles in their frames, and it consists in the particulars hereinafter pointed out and claimed.

In the drawings Figure 1 is a side view, partly in section, and partly broken away, of a window frame, showing two pivoted sashes held at an angle by my improved sash guide; Fig. 2 is a front view of a portion of the frame, sashes and guide; Fig. 3, is an enlarged view, partly in section, of the guide; Fig. 4 is a view of a cross section 20 through the side of the frame, partly broken away and showing the guide from above and its relation to the frame and sashes; and Fig. 5 is a cross section taken on the line X—X of Fig. 3, looking in the direction of the arrows.

The same parts are referred to by corresponding reference numerals in all the figures.

The window frame 1 is preferably formed of sheet metal and is provided with grooves 2, 3, at each side, to receive the sash pivots 4, 5 and also to accommodate the sash chains, not shown. The groove 2 is provided with inturned edges 6, 6, which are shown as formed by the edges of a split tube, 7 which is riveted into the groove in the side of the frame. A bar 8 is pivoted at its lower end, by a pin 9, pressed to duty by a spring 10, in a forked support 11 secured to the top of the lower sash 12.

Through the upper end of the bar 8 passes, loosely, the reduced end 13 of the tubular arm 14 which carries the head 15, provided with the undercut extension 16.

And longitudinally through the arm 14 passes the shank 17, threaded at one end to receive the nut 18, and being squared and extended at its other end into the head 19.

A grooved, anti-friction roller 20, carrying 50 a ring 21 of rubber or other yielding material, is also mounted on the arm 14, upon which it normally revolves. The heads or extensions, 16, 19, lie within the groove 2, the edges of which enter the grooves between 55 the portions 16, 19 and the head 15. And, normally, the heads may slide up and down

in relation to the groove 2, as the lower sash is raised, lowered or tilted. When, however, the lower sash has been placed at any selected angle it is desirable to secure it in position, so that it may not be easily dislodged by sudden drafts or by accidental causes. And this may be accomplished by turning the nut 18 upon the shank 17 so as to draw it outward through the arm 14, 65 clamping the head 19 against the inside of the edges of the groove 2, so as to grasp the edges between the head 19 and the head 15, and preventing the sliding of the heads up or down in the frame groove. This movement of the nut causes it to clamp the upper end of the bar 8 between itself and the anti-friction wheel 20, which is held laterally by the shoulder 22 on the shank 17, whereby the bar 8 is prevented from swinging around 70 the arm 14 and is held in whatever position it has been placed. This locking of the sash guide in the frame groove also prevents the raising or lowering of the sash without loosening the nut 18, permitting the window 80 to be partly opened and still locked, or to be locked in its closed position without the use of a special lock.

The upper sash 23 which counterbalances the lower sash 12, in the usual manner, by 85 being connected thereto on each side by a chain (not shown) attached to the pivots 4 and 5, running in the grooves 2 and 3 and over an overhead pulley (not shown), rests, when tilted forward, against the rubber 90 ring on the anti-friction roller 20, against which it can travel, as the sashes are raised and lowered, without marring or defacing the sash.

The use of the spring-pressed pin 9 to 95 connect the bar 8 with the lower sash permits the bar to be readily disconnected whenever it is desired to turn the sash inward for cleaning, or to remove it from the window frame. And by combining these 100 detachable and locking features in the sash guide I secure an arrangement whereby the sashes may be simply and effectually locked in desired positions, and, at the same time, the lower sash may be quickly freed from 105 the guide.

Having thus described my invention what I claim and desire to secure by Letters Patent of the United States, is:

1. The combination, with a window frame, 110 provided with an undercut groove therein, of a guide having clamping elements adapted

to grip the edges of the groove between them and embodying a head disposed outside of the groove and a relatively retractable portion disposed within the groove, and adjustable means connecting said guide with a pivoted sash.

2. The combination, with a window frame, provided with an undercut groove therein, of a guide having clamping elements adapted 10 to grip the edges of the groove between them and embodying a head disposed outside of the groove with a reduced neck and an enlarged portion disposed within the groove and a relative retractable portion also disposed within the groove, and adjustable means connecting said guide with a pivoted sash.

3. The combination, with a window frame, provided with an undercut groove therein, 20 of a guide embodying clamping elements adapted to engage the edges of said groove,

means for connecting said guide with a sash, and common means for clamping the guide in the sash groove and locking the sash connecting means.

25

4. The combination, with a window frame, provided with an undercut groove therein, of a guide embodying a head slidably connected with said groove and carrying a clamping element, an anti-friction bearing 30 for an upper sash, comprising a roller, carried by the sash guide, a bar pivoted to the sash guide at one end and at the other to a lower sash, and means comprising a threaded shank and a nut for simultaneously clamping the guide in the sash groove and locking the bar at a definite angle.
